UNITED STATES PATENT OFFICE.

JOHN M. YOUNG, OF BROOKLYN, NEW YORK, ASSIGNOR TO AMERICAN CAN COMPANY, OF NEW YORK, N. Y., A CORPORATION OF NEW JERSEY.

PROCESS OF LINING CAN ENDS AND GASKET-LINED ENDS.

Application filed July 29, 1922. Serial No. 578,338.

To all whom it may concern:

Be it known that I, JOHN M. YOUNG, a citizen of the United States, residing in Brooklyn, in the county of Kings and State of New York, have invented a new and useful Improvement in Processes of Lining Can Ends and Gasket-Lined Ends, of which the following is a specification.

My invention relates in general to a process of lining can ends adapted for use upon hermetic containers and to an improved end of this character lined in accordance with said process.

It is customary to employ, in the seam between the end and body of a can in which food products are packaged, a gasket which serves to provide an hermetic seal when the flanges of said end and body are interfolded in the usual double seam. Various types of gaskets have been employed for this purpose, the usual type being a paper ring which is cut and applied to the flange of the can end prior to its assembly with the body. Liners of this character have not been, in all respects, satisfactory, due to certain defects in the material itself and to certain difficulties in incorporating it in the seam. In other words, the paper, being absorbent, sometimes becomes saturated with the liquid contents of the can during the seaming operation and, upon subsequently drying out, contracts, leaving small passages through which air may pass; also, the inexact position of such a gasket may result in irregularities which give rise to the same difficulty.

In attempting to provide a more perfect gasket material, various compounds, usually containing a composition of rubber or like substance, have been tried, being ordinarily applied to the flange of the can end in liquid form and dried to the consistency desired. For various causes, however, these compounds have not been entirely successful, either because of their being affected by the contents of the can, or being of such composition as to permit slight leaks in the finished seam.

It has, therefore, been proposed to use a combination of a fibrous gasket with a rubber, or other water protective solution and, for this purpose, the paper sheets, from which the gaskets are cut before application to the can ends, have been treated with such solution to provide the desired combination.

A disadvantage of great importance was attendant upon this process, however, since there is necessarily a considerable amount of scrap left after the paper rings are cut from such sheets and, not only was the solution which went into this scrap entirely lost, but, for practical purposes, the scrap paper was also lost, since, when so treated, it could not be sent back to paper mills for other use.

It is, therefore, a principal object of the present invention to provide a process of lining can ends in which the paper is saturated with paraffine, or any compound which will prevent absorption of moisture or passage of air, after it is positioned in the flange of the can end and the stock from which the gaskets are cut is, therefore, not impaired and can be returned to the mill to be worked over into paper for more gaskets. In this connection, the invention contemplates a process in which the end flange is first lined with paraffine or the like, the fiber gasket then seated and a heated ring or member applied to melt the paraffine and cause it to saturate the gasket.

Another object of the invention is the provision of a can end in which a fibrous gasket is seated in particularly effective manner and so treated as to render it resistant to penetration of moisture and air, thus providing an improved form of gasket seal.

Other objects and advantages of the invention will be apparent as it is better understood from the following description, which, taken in connection with the accompanying drawings, discloses a preferred embodiment thereof.

Referring to the drawings,

Figure 1 is a vertical section taken through the compound lining machine by which the paraffine, or other compound, is deposited in the can end flange;

Fig. 2 is a sectional view of a part of the lining machine for applying fibrous gaskets;

Fig. 3 is a similar view, showing the manner in which a hot iron is employed to melt the paraffine, or other compound, in the end flange; and

Fig. 4 is an enlarged section of the flange of a can end lined in accordance with my invention.

As a suitable type of apparatus by which

my invention may be employed, I have shown, in Fig. 1, a portion of a compound lining machine, which comprises primarily a frame 11, in which is mounted a rotatable 5 end support 12, a reservoir 13 being sustained above said support and having in the bottom thereof one or more applying disks 14 by which the compound contained in the reservoir is adapted to be deposited in the 10 cup-like recess of the peripheral flange 15 (Fig. 4) upon the can end 16. Said end 16 is held in inverted position upon the support 12 by means of a head 17 rotatably mounted upon a plunger 18, suitable ball 15 bearings 19 being provided to facilitate rotation of said head and of the support 12 which turns in cooperation with the applying disks 14. The disk 14 is mounted upon a pin, or shaft 21, having bearings in the 20 bottom plate 22 of the reservoir, and this shaft is rotated, to cause the lining action of the disk 14, by means of a bevel gear 23 meshing with a gear ring 24, which is secured by means of an annulus 25 and a 25 screw 26 to an actuating ring 27. It will be understood that suitable mechanism is provided for the operation of the actuating ring 27, this preferably being controlled by means for feeding the can end to the support 12, this mechanism, however, not being 30 shown, since it forms no part of the present invention. The support 12 is lowered and raised in a known manner, after each such 35 operation on a can end, so as to allow the discharge of the treated can end, the reception of a new can end and the clamping and rotation of the latter against the head 17 and in the sphere of operation of the disks 14.

40 The disk 14 is provided with a series of peripheral pockets 28 which deliver measured quantities of the lining material from the reservoir 13 to the flange of the can end when said disk is rotated. By means of 45 the foregoing apparatus, or other suitable mechanism, I deposit upon the peripheral flange of the can end a suitable quantity of paraffine, or other water protective compound, and it will be understood that this 50 operation is completed prior to the delivery of the can ends to the usual paper gasket lining machine.

Referring now to Fig. 2, showing a part of such lining machine, it will be noted that 55 a paper gasket 29 is forced into the flange of the can end by means of a seating die 31, said gasket being supported upon a ledge 32 in a frame part 33 prior to its being seated in the end flange by the member 31. Said member 31 is carried upon a rod 34 and actuated in any preferred manner, and an 60 end support 35, of any suitable character, is provided for the support of the can end during the gasket seating operation. Upon 65 completion of this operation, the ring liner

29 will be positioned above a layer of paraffine, or compound, 36 and, in this condition, the gasket is subjected to the action of the heating iron 37, shown in Fig. 3, said iron being preferably heated by electricity and suitably insulated connections 38 being provided for necessary wiring. The heat serves to fuse the paraffine, or other material beneath the fibrous gasket, which becomes impregnated by penetration of the liquid, which also spreads to the outer edge of the paper ring, as indicated at 39, and serves to seal said ring to the can end, not only at the base of the flange, as indicated at 41, but also around the edges, by means of the part of the substance 39 which fills the space between the edge of the gasket and the curled flange.

The gasket so formed not only prevents absorption of moisture, but also is less easily penetrated by air and is held in desired relationship, so that, when the end is applied to a can body, a greatly improved hermetic seal is obtained.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. The process of gasket lining can ends which comprises lining the peripheral flange of the end with a fusible compound, placing in said flange upon the compound, a thin absorbent gasket suitable to be interfolded in a double seam, and applying heat to said gasket whereby the compound is melted and caused to saturate the fibrous gasket rendering the same resistant to the penetration of moisture and air.

2. The process of gasket lining can ends which comprises lining the peripheral flange of the end with a fusible compound, placing in said flange with said compound, a thin absorbent gasket suitable to be interfolded in a double seam, and applying a heated member to said gasket whereby the compound is melted and caused to saturate the fibrous gasket rendering the same resistant to the penetration of moisture and air.

3. The process of gasket lining can ends which comprises lining the peripheral flange of the end with paraffine, placing in said flange upon the paraffine, a thin absorbent gasket suitable to be interfolded in a double seam, and applying heat to said gasket whereby the paraffine is melted and caused to saturate the fibrous gasket rendering the same resistant to the penetration of moisture and air.

4. The process of gasket lining can ends which comprises separately lining the peripheral flange of the end with a fusible compound and with a fibrous thin, absorbent 5 and pliable gasket, and applying heat to said lining substances whereby the compound is melted and penetrates said gasket.

5. The process of gasket lining can ends which comprises separately lining the peripheral flange of the end with a fusible liquid proofing compound and with a thin, flexible and absorbent gasket, and applying heat to said lining substances whereby said compound which is thus melted is caused to 10 saturate the absorbent gasket rendering the same resistant to the penetration of moisture and air.

6. The process of gasket lining can ends which comprises first depositing a layer of 20 fusible compound in the flange of the end, placing a thin paper ring in said flange, and fusing the compound to cause it to penetrate the ring and to seal the same to the can end.

7. A can end having a peripheral flange 25 adapted to be seamed to a can body to form an hermetic seal, said flange being lined with fusible compound and with a thin absorbent ring, said ring being impregnated by melting said compound and thus rendered resist- 30 ant to the penetration of moisture and air

and pliable for interfolding in a double seam.

8. A can end having a peripheral flange adapted to be seamed to a can body to form an hermetic seal, said flange being lined with 35 a fusible compound and having a thin absorbent gasket placed therein and impregnated with said compound by application of heat to said fusible lining.

9. A can end having a peripheral flange 40 adapted to be seamed to a can body to form an hermetic seal, said flange being lined with a fusible compound and a thin absorbent gasket placed therein and impregnated and sealed to the can end by application of 45 heat to said fusible lining and made pliable for interfolding in a double seam.

10. A can end for application to a can adapted to be hermetically closed, said end having a peripheral flange adapted to be 50 interfolded with the can body to close the can, said flange being lined with a fusible liquid proofing compound and having a thin paper gasket positioned therein, said gasket being penetrated with said compound and 55 sealed to the can end by application of heat to the compound in the flange, said gasket being pliable for interfolding in an hermetic double seam.

JOHN M. YOUNG.
